ANTENNA AND MATCHING CIRCUIT

Nils E. Lindenblad, Port Jefferson, N. Y., assignor
to Radio Corporation of America, a corporation
of Delaware

Application September 12, 1946, Serial No. 696,556

13 Claims. (Cl. 250—33)

1

The present invention relates to antenna systems and more particularly to an improved circuit for matching a transmission line to an antenna.

An object of the present invention is the provision of an antenna system which exhibits broad band characteristics.

A further object of the present invention is the provision of an antenna which may be utilized as the energized member of an array of reflectors and directors.

Still a further object of the present invention is the provision of a simple means for matching a transmission line to a broad band antenna.

Another object of the present invention is the provision of a matching system which will enable the matching of a transmission line to an antenna over a wide range of conditions by a simple adjustment of the proportions of parts of the matching circuit.

The foregoing objects and others which may appear from the following detailed description are attained by providing an antenna in the form of a hollow conductive member having transverse dimensions which are large in terms of the operating wavelength. Ordinarily the radiator will be so positioned as to extend perpendicularly away from a conductive sheet. A coaxial transmission line is arranged to pierce the ground sheet and extend into the hollow interior of the radiator. The inner conductor of the transmission line is so arranged to extend further into the hollow interior of the radiator than the outer shell. By proportioning the relative extensions of the outer shell and inner conductor into hollow interior of the radiator, the input impedance of the radiator may be easily matched to any convenient transmission line impedance. The protrusion of the inner conductor beyond the outer conductor of the transmission line is smaller the higher the matching impedance required. The outer conductor of the transmission line is at the same time longer.

The present invention will be more fully understood by reference to the following detailed description which is accompanied by a drawing in which:

Figure 1 illustrates in transverse cross section an elementary type of vertical radiator known in the art which is utilized as a basis for the matching circuit of the present invention, while

Figure 2 illustrates in transverse section an embodiment of the present invention, and

Figures 3 and 4 illustrate modifications thereof.

Referring now to Figure 1 there is shown a conductive sheet GP which may under some

circumstances be the outer conductive skin of an airplane or it may be a flat metal roof on the top of a tall building. Beneath ground plane GP is a concentric transmission line having an outer shell 10 and an inner conductor 12. The transmission line extends through the ground sheet GP at right angles to the plane of the sheet to form a quarter wave antenna. The outer shell 10 of the transmission line may extend approximately one third of the distance up from the ground sheet GP as a sleeve 20 while the inner conductor extends a further distance as a radiator 22. The overall length of the radiating portion of the antenna is approximately one quarter wavelength at the operating frequency.

In Figure 2 the ground sheet and transmission line arrangement is the same as described with reference to Figure 1. However, in this modification the radiator itself is in the form of a hollow conductive member 19 closed at the top and connected to ground plane GP by connection 18. It is preferred that member 19 have a transverse dimension which is fairly large in terms of the operating wavelength; for example, somewhere between one eighth and three sixteenths of the operating wavelength. The radiator 19 thus possesses broad band characteristics. The overall length of radiator 19 is approximately a quarter wavelength. The transmission line is coupled to the interior of radiator 19 by the extension of sleeve 20 and extending conductor 22 within the hollow interior of radiator 19. Sleeve 20 is provided with an upper slidable sleeve 21 and member 22 is provided with a slidable outer sleeve 23 whereby the relative extensions of these members within the radiator 19 may readily be adjusted. By adjusting these extensions the effective impedance of the antenna, as seen from the transmission line TL, may be adjusted to perfectly match the radiator 19 to the transmission line. The approximate voltage distribution over the outside of the radiator 19 is indicated by curve E.

In Figure 3 the radiator is in the form of a dome or bell-shaped member 29 having a flange 30 around its lower edge. The flange 30 is electrically and mechanically connected to the ground plane GP. The transmission line arrangement in Figure 3 is the same as in Figure 1. As so far described the arrangement of Fig. 3 permits the coupling of the transmission line TL to the interior of radiator member 29 but in the absence of any communication between the interior and exterior of member 29 no radiation would be possible. Therefore, I have provided a series of apertures or circumferentially extending

slots 31 around the base of the radiator member 29 by means of which the interior thereof may be coupled to the exterior. The outside dimensions of radiator 29 and the extent of the coupling provided by slots 31 effects to some extent the required extension of sleeve 20 and inner conductor 22 into the interior of radiator 29 to provide a match to any given transmission line. However, where a 50 ohm transmission line is used the outer sleeve 20 of the transmission line may extend over two thirds of the length of the inner conductor within radiator 29 and above ground plane GP while the inner conductor may extend nearly to the top of member 29. It will thus be seen that I have provided a radiator which is sturdily constructed while still having a broad band characteristic. The excitation system permits a wide range of impedance transformation and reactance balancing.

Figure 4 shows a further modification of Figure 2. Here radiator 39 is similar to radiator 19, except that it is approximately a half wave in length. The transmission line arrangement within the radiator is the same as in previous figures except that due to the greater length of radiator 39, it terminates at somewhere near the center thereof. The interior of radiator 39 is coupled to the exterior by apertures 41 at the midsection.

While I have illustrated a particular embodiment of the present invention, it should be clearly understood that it is not limited thereto since many modifications may be made in the several elements employed and in their arrangement without departing from the spirit and scope of the invention.

What is claimed is:

1. A broad band antenna system including a radiation transferring element comprising an elongated hollow conductive member closed at one end and arranged substantially normal to one side of a conductive ground plane system, and means to transfer energy from said hollow member to a utilization device, said means comprising a length of coaxial transmission line of given characteristic impedance having sleeve and inner conductors extending into said hollow member, said sleeve conductor being connected to said ground plane system and said inner conductor extending into said hollow member to a greater distance than said sleeve conductor, the distances of the extension of said conductors into said hollow member having values at which the impedance of said hollow member at the operating wavelength is substantially matched to said given characteristic impedance of said coaxial transmission line section, the sole coupling between said inner conductor and said hollow member being by radiation of energy therebetween.

2. An antenna system including a radiation transferring element comprising an elongated hollow conductive member closed at one end and arranged to one side of a conductive ground plane system, said hollow conductive member having longitudinal and transverse dimensions large in terms of the operating wavelength and having the longitudinal dimensions extending in a direction substantially normal to said ground plane system, and means to transfer energy from said hollow member to a utilization device, said means comprising a length of coaxial transmission line of given characteristic impedance having sleeve and inner conductors extending into said hollow member, said sleeve conductor only

being connected to said ground plane system and said inner conductor extending into said hollow member to a greater distance than said sleeve conductor, the sole coupling of said inner conductor to said hollow member being by radiation of energy therebetween, the distances of the extension of said conductors into said hollow member having values at which the impedance of said hollow member at the operating wavelength is substantially matched to said given characteristic impedance of said coaxial transmission line section.

3. An antenna system including a radiation transferring element comprising an elongated hollow conductive member closed at one end and arranged to one side of a conductive ground plane system, said hollow conductive member having longitudinal dimensions of at least a quarter of the operating wavelength extending in a direction substantially normal to said ground plane system transverse dimensions of at least an eighth of the operating wavelength, and means to transfer energy from said hollow member to a utilization device, said means comprising a length of coaxial transmission line of given characteristic impedance having sleeve and inner conductors extending into said hollow member, said sleeve conductor only being connected to said ground plane system and said inner conductor extending into said hollow member to a greater distance than said sleeve conductor, the distances of the extension of said conductors into said hollow member having values at which the impedance of said hollow member at the operating wavelength is substantially matched to said given characteristic impedance of said coaxial transmission line section, said inner conductor being free of any direct current connection to said hollow member.

4. A broad band antenna system including a radiation transferring element comprising an elongated hollow conductive member closed at one end and arranged substantially normal to one side of a conductive ground plane system, the end of said hollow member remote from said one end being connected to said conductive ground plane system, there being apertures therein interconnecting the interior of said hollow member with ambient space, and means to transfer energy from said hollow member to a utilization device, said means comprising a length of coaxial transmission line of given characteristic impedance having sleeve and inner conductors extending into said hollow member, said sleeve conductor only being connected to said ground plane system and said inner conductor extending into said hollow member to a greater distance than said sleeve conductor, the distances of the extension of said conductors into said hollow member having values at which the impedance of said hollow member at the operating wavelength is substantially matched to said given characteristic impedance of said coaxial transmission line section, the sole coupling between said inner conductor and said hollow member being by radiation of energy therebetween.

5. An antenna system for operation in conjunction with a conductive ground sheet, including an elongated conductive dome having a flange at the base thereof and a plurality of circumferentially extending slots therein near the base, a length of coaxial transmission line having sleeve and inner conductors extending into said dome, said sleeve conductor being electrically connected to said flange, said inner conductor extending into said dome to a greater distance

than said sleeve conductor and being free of any direct current connection to said conductive dome.

6. An antenna system for operation in conjunction with a conductive ground plane system, including a hollow, substantially closed, elongated conductive member having a plurality of circumferentially arranged slots therein, a section of coaxial transmission line of given characteristic impedance and having sleeve and inner conductors extending into said hollow conductive member with the inner conductor extending therein a greater distance than the sleeve conductor, the sleeve conductor being connected to said conductive member at the point of entry therein, and said member being connected to said conductive ground plane system, the degree of extension of said conductors into said hollow member having a value at which the operating impedance of said hollow member is substantially matched to the characteristic impedance of said coaxial transmission line, the sole coupling between said inner conductor and said hollow member being by radiation therebetween.

7. A broad band antenna system for operation in conjunction with a conductive ground sheet, including an elongated conductive dome having a flange at the base thereof and a plurality of slots therein near the base, a length of coaxial transmission line having sleeve and inner conductors extending into said dome, said sleeve conductor being electrically connected to said flange, said inner conductor extending into said dome to a greater distance than said sleeve conductor, the sole connection between said conductors and said dome being a connection of said sheath conductor to said ground slot substantially at said flange.

8. A broad band antenna system for operation in conjunction with a conductive ground plane system, including a hollow substantially closed, elongated conductive member having a plurality of circumferentially arranged slots therein and being connected to said conductive ground plane system, a section of coaxial transmission line having sleeve and inner conductors extending through said ground sheet and into said hollow conductive member with the inner conductor extending therein a greater distance than the sleeve conductor, the sleeve conductor being connected to said conductive member at the point of entry therein to form the sole direct connection between said conductors and said conductive member.

9. A broad band antenna system for operation in conjunction with a conductive ground sheet, including an elongated hollow conductive member closed at one end and arranged substantially normal to the plane of said ground sheet, there being at least one aperture near the lower end of said hollow member and said ground sheet, a section of coaxial transmission line having sleeve and inner conductors extending through said ground sheet into said hollow conductive member, said inner conductor extending into said hollow conductive member to a greater distance than said sleeve conductor, said inner conductor being free of connection with said conductive member, and the end of said conductive member adjacent said ground sheet and said sleeve conductor being connected to said ground sheet.

10. An antenna system for operation in conjunction with a conductive ground sheet, including an elongated hollow conductive member closed at one end and arranged substantially

normal to the plane of said ground sheet, and a section of coaxial transmission line having sleeve and inner conductors extending into said hollow member, said sleeve conductor being connected to said ground sheet, said inner conductor extending into said hollow conductive member to a greater distance than said sleeve conductor, and said inner conductor being free of connection with said conductive member.

11. An antenna system for operation in conjunction with a conductive ground sheet, including an elongated hollow conductive member closed at one end and arranged substantially normal to the plane of said ground sheet, a section of coaxial transmission line having sleeve and inner conductors extending into said hollow conductive member, said inner conductor extending into said hollow conductive member to a greater distance than said sleeve conductor, said inner conductor being free of connection with said conductive member, said conductive member having apertures therein, and the end of said conductive member adjacent said ground sheet and said sleeve conductor being connected to said ground sheet.

12. An antenna system for operation in conjunction with a conductive ground sheet, including an elongated hollow conductive member closed at one end and having the other end connected to said ground sheet, a section of coaxial transmission line having sleeve and inner conductors extending into said hollow conductive member, said inner conductor extending into said hollow conductive member to a greater distance than said sleeve conductor, said inner conductor being free of connection with said conductive member, said conductive member having apertures therein near the point of connection to said ground sheet and said sleeve conductor being connected to said ground sheet.

13. An antenna system for operation in conjunction with a conductive ground sheet, including an elongated hollow conductive member closed at both ends and arranged substantially normal to the plane of said ground sheet, a section of coaxial transmission line having sleeve and inner conductors extending into said hollow conductive member, said inner conductor extending into said hollow conductive member to a greater distance than said sleeve conductor, said inner conductor being free of connection with said conductive member, said conductive member having apertures therein substantially midway of the ends thereof, and the end of said conductive member adjacent said ground sheet being connected to said ground sheet by said sleeve conductor.
